IMPROVEMENT IN NARROW-WARE LOOMS.

L. J. KNOWLES, OF WARREN, MASSACHUSETTS.

Letters Patent No. 60,388, dated December 11, 1866.

The Schedule referred to in these Letters Patent and making part of the same.

TO ALL PERSON TO WHOM THESE PRESENTS SHALL COME:

Be it known that I, LUCIUS J. KNOWLES, of Warren, in the county of Worcester, and State of Massachusetts, have made a new and useful invention having reference to Looms for Weaving Ribbons or Tapes; and do hereby declare the same to be fully described in the following specification, and represented in the accompanying drawings, of which—

Figure 1 is a top view of a loom containing my invention.

Figure 2 is a front elevation.

Figure 3 is a transverse section; and

Figure 4, a longitudinal section of it.

This latter section being taken through the lay, and lengthwise thereof.

In the drawings, A denotes the frame of such a loom, B its lay, and C its cranked shaft for actuating the lay, such shaft being provided with two bell-crank, *a a*, connected with the lay in the ordinary manner by pitmen or connecting rods, *b b*. The lay-rack is shown at D, as arranged within a groove, *c*, made in the race-beam *d* of the lay. Two leather, or other proper straps, *e e*, are attached to the rack near its two opposite ends. Each of these straps passes along underneath the rack a short distance to and partly around one of two guide-wheels, *f f*, arranged in the race-beam *d*, in manner as exhibited in fig. 4. From the said wheel the strap descends and passes underneath and against one of another pair of guide-wheels, *g g*, arranged in guides, *i i*, projecting from the swords *h h* of the lay. The two straps are connected by rods, *k k*, with a link, *l*, through the middle of which the pin *m* of a crank, *n*, is inserted. The said crank projects from the lower end of an inclined shaft, *o*, suitably supported in bearings, *p p*, extending from an inclined brace or bar, *F*, going from the back lower girt to the front upper girt of the loom frame. The cranked shaft is represented as supported in three boxes, *r s r*, the middle one, *s*, of such boxes being upheld by the inclined brace *F*. A bevel gear, *t*, fixed on the upper end of the shaft *o*, engages with a bevelled pinion, *u*, fixed on the cranked shaft, this latter shaft having, while the loom is in operation, a constant rotary motion, will impart such a movement to the inclined shaft, whose crank, while revolving, will so move the link *l* as to cause it to alternately pull on the straps *e e*, and produce reciprocating longitudinal movements of the lay-rack.

The above described invention is the subject of a patent numbered 54,742, and granted to me on 15th day of May, A. D. 1860, such invention being a new or improved mechanism for operating the lay rack for communicating motion to the various shuttles of a tape loom.

Instead of forming the link *l* of such mechanism with a cylindrical hole to receive the wrist *m* of the crank *n*, I now form such link with an elongated slot or groove, *v*, going through it, and being to receive the wrist *m*. This elongated hole allows or causes the lay rack, to remain at rest a short period of time before each longitudinal movement of it takes place. This stoppage of the lay rack for a while at each of the extremes of its movement, is found to be essential and of advantage in the weaving of certain kinds of tapes or goods. The tapes, passing down from the breast beam *E*, are led around a series of rollers, *F' F' F'*, and between them and a series of pressure rollers, *G G G*. Each of such pressure rollers is supported by means of a hanger, *H*, arranged at an acute angle with the lower surface of the breast beam, that is, in manner and with respect to the take-up roller, with which such roller, *G*, operates, as represented in fig. 3. The hanger *H* is to be hinged to the breast beam in order that the roller of such hanger may be moved up and down in a circular arc, whose centre is at the junction of the hanger and the breast beam. This application of each top or pressure roller to the loom, viz: by an inclined hanger, is of great advantage, as it enables the roller to be readily moved off and above its fellow roller, the same being accomplished simply by pressing the top roller forward. In constructing the series of take-up rollers, I form each set of them of a series of annuli, *z z z*, and two short cylinders, *y y*; arranged at equal distances apart, and connected by a series of parallel bars or connectors, *w w w*, disposed at equal distances apart, and in manner as shown in figs. 2 and 3, and also in figs. 5 and 6, one of which is a longitudinal section of the two sets or series of take-up rollers, the other being a transverse section of one of such sets. Each of such series of rollers I form with one long journal, *z*. The inner one of the series I make.

with another journal, a' , to rest on a central bearing, b' . The journal a' also has a round head, c' , cast on it, and such journal projects beyond this head, and into a corresponding socket, d' , made axially in the first roller of the next series of take-up rollers. A stud, f' , projecting from the side of the said inner roller, enters a corresponding hole made in the head c' . By thus connecting the two series of rollers they will operate to better advantage than when conjoined separately, in case of wear of the central journal and its bearings.

What I claim as of my invention is as follows:

I claim the combination of the slot v , or its equivalent, with the mechanism, substantially for operating the lay-rack, as set forth, such mechanism consisting not only of the link l , the straps e , and their guide-wheels as applied to the lay and its rack, substantially as described; but of the crank n , the shaft o , and the bevel gears t u , or their mechanical equivalent or equivalents, operated by the cranked shaft of the lay.

I also claim the above described mode of making each of the series of take-up rollers, viz: of two heads, a series of annuli and cross bars, or connectors, as set forth.

I also claim the application of each of the top or pressure rollers to the loom, viz: by means of an inclined hanger, to operate substantially as described.

I also claim the application of one series of take-up rollers to the other series thereof, substantially in manner as described, that is, by means of the head c' , the journal a' , socket d' , and stud f' , arranged and applied to the two series as set forth.

L. J. KNOWLES.
